UNITED STATES PATENT OFFICE.

RICHARD A. ROBERTS, OF BROOKLYN, NEW YORK.

CONSTRUCTION OF VESSELS.

SPECIFICATION forming part of Letters Patent No. 573,297, dated December 15, 1896.

Application filed June 18, 1896. Serial No. 595,971. (No model.)

To all whom it may concern:

Be it known that I, RICHARD A. ROBERTS, a citizen of the United States, residing at Brooklyn, in the county of Kings and State of New York, have invented certain new and useful Improvements in the Construction of Vessels; and I do declare the following to be a full, clear, and exact description of the invention, such as will enable others skilled in the art to which it appertains to make and use the same, reference being had to the accompanying drawings, and to the letters of reference marked thereon, which form a part of this specification.

The object of this invention is to increase the speed of boats or vessels, and especially vessels of light draft and considerable length of beam; and this object is attained by means of self-filling cavities or air-chambers which are situated at the bottom of the vessel and by air-channels which run from one end of the vessel to the other and are adapted to receive and hold for a brief period of time bodies of air which enter the forward end of said air-channels as the vessel moves in her course. The air in the cavities or chambers and in the channels increases the buoyancy of the craft, and consequently decreases the surface which is exposed to the water. The surface of the boat which is in contact with the water being thus reduced, the adhesion between the boat and water, as well as the friction between these two bodies when the boat is in motion, is also reduced. Furthermore, the area of contact between the boat and the water is still further lessened by the fact that portions which would otherwise be in contact with the water are in contact with bodies of air which rest upon the water. The advantages flowing from the facts just related will be apparent when it is remembered that one of the great obstacles to high speed in boats is the great force of adhesion which exists between water and any body which it will wet; that the friction between water and the body of a vessel is a great factor in retarding the motion of the boat, and that in proportion as the area of surface which is in contact with the water is increased the adhesion and friction aforesaid are magnified.

A vessel in motion carries with her a thin film of water, between which and the bottom of

the vessel there is adhesion which is stronger than the cohesion which exists between the film of water and the main body of water in which the vessel is floating, that is to say, the adhesion between the molecules of water and the adhesion between the molecules of a solid which it wets is stronger than the cohesion which exists between the molecules of the water itself. The planes of clearage are therefore not coincident with those of the bottom of the vessel, and the film of water which the vessel carries is therefore as thick as the distance between their respective planes. It is therefore true that anything which lessens the area of contact between the vessel and the water, or which places in contact with the water a body such as air, between which and the water there is less adhesion and friction than there is between the water and bottom of the vessel itself, must in a greater or lesser degree remove some of the natural obstacles to the vessel's progress.

In the accompanying drawings, Figure 1 is a plan view of the bottom of a vessel, showing the several keels, the corrugations, and the ducts constituting means for directing air to the chambers. Fig. 2 is a longitudinal sectional view taken on the line $z-z$ of Fig. 1. Fig. 3 is a view in cross-section taken on line $y-y$ of Fig. 1, both of which latter views illustrate the construction and position of the air-chambers. Figs. 4, 5, 6, 7, and 8, are enlarged detail views of certain modifications of my invention. Figs. 9 and 10 illustrate my invention as used in a particular kind of boat herein described.

A is the main central keel of the vessel, on either side of which are arranged the keels B, extending parallel therewith and at uniform distances therefrom, the spaces between all the keels varying according to the size of the vessel. As shown in Fig. 1, five keels are used, but more or less may be employed in accordance with different sizes and other conditions of vessels to which they are applied. In all cases, however, these keels should preferably begin above the water-line, and should be of sufficient depth, that is from the vessel's bottom to their extreme edges, to serve the purposes for which they are intended.

Corrugations C are arranged transversely of the bottom of the vessel extending between

the outside keels the extreme width of the bottom. They may be of any form and depth desired. I make no claim to any particular form, but broadly claim these corrugations, 5 because the advantages of any specific construction thereof can only be determined by experimenting with different classes of vessels under different extrinsic conditions. These corrugations are more specially adapted, however, to smaller boats which never attain a higher speed than six miles an hour, because the corrugations are not only sufficient for the purpose but occupy no considerable space. They may though, as shown, be used in vessels of larger size in conjunction with the air-chambers, which I shall now proceed to describe. These air-chambers D are arranged between the bottom proper, E, of the vessel and the false bottom F thereof, which is supported and strengthened by the keels A and B. In Fig. 2 partitions H are shown, which divide the channels formed by the keels A and B between the bottom E and false bottom F into uniform chambers or compartments D. These compartments have exterior communication through the ducts or passages K, which may be arranged at an incline, Fig. 4, or may merely amount to perforations in a very thin false bottom O, Fig. 5. The 30 compartments are otherwise air-tight. Between each pair of ducts in a single groove the false bottom, if not corrugated, may be curved convexly, as shown in Fig. 5, so that air directed through said grooves or channels 35 may more easily enter ducts K.

The chambers or compartments are constructed, as above stated, as wide as the space between each pair of keels, and the ducts communicating therewith may be just as wide and 40 preferably so, but in Figs. 1 and 2 at L these ducts are illustrated as extending longitudinally and as not being so wide as the space between the keels, and they communicate with the chamber M, which is preferably longer than chambers D.

In Figs. 7 and 8 but a single air-chamber is used, extending from dotted line N' sternward and having exterior communication through its only entrance, a longitudinal duct 50 N. L-shaped portions L' are arranged between the keels, so as to form sides for the duct N. Secured to each side of the downwardly-extending flanges of these L-shaped portions situated contiguous to the duct is the false bottom F, having transverse corrugations. Under the vessel's bow, there being here no air-chamber or its duct, the corrugations may extend the entire distance between keels. I do not wish to limit myself 55 to the employment conjointly of the longitudinal duct and corrugations. For the auxiliary corrugations arranged on each side of the longitudinal duct, as above described, transverse ducts may be substituted, if desired. Attention is called to the fact that the duct, as shown in this Fig. 8, may be so constructed that there is a considerable space

between its mouth and the air-chamber with which it communicates. In larger vessels difficulty would be encountered in cleaning 70 the inside of the chambers, which would soon become affected in various ways by the action of the water and its deposits. By the arrangement above referred to the duct is of such depth that the air allowed to enter may not 75 only be contained by the chamber but may also partly fill this duct, so as to prevent water from entering the chamber.

It is apparent that chambers instead of corrugations are better adapted for larger vessels, which can more readily afford the sacrifice of some space for a contrivance of this character than can small boats, and which usually move at a speed which overcomes the purpose when merely corrugations are 85 employed. Hence chambers instead of corrugations are more applicable to larger vessels.

It is obvious that the keels which I have described as extending above the water-line at the bow would not only serve to break the 90 impulse of the waves by dividing them, and hence lessen their retarding force against the vessel at this point, but while the vessel is moving at a comparatively high rate of speed or while in rough waters these keels forming 95 channels would be especially advantageous toward accomplishing the object of this invention—viz., conducting air which is introduced and forced into the channels by the water at the bow and beneath the vessel's 100 bottom to be detained there by the means provided and for the purposes described.

In Fig. 6 is illustrated a means whereby the bottom f of the chambers may be detachably arranged in their respective grooves. A 105 centrally-situated transverse flange h, corresponding to the partition H before described, is made integral with the bottom f. On opposite sides of the grooves and on the inner faces of the keels at a convenient distance 110 from the bottom of the vessel brackets o' are provided, to which the bottom f may be screwed or by any other means detachably secured.

I have shown in Figs. 9 and 10 a particular 115 type of boat to which my invention is applicable and which is especially adaptable either as a bathing-boat or an individual life-raft. The longitudinal keels A' and B' are in this case arranged in pairs, the said pairs being 120 braced by and secured to a piece of board E' or other light material of suitable size. The individual keels of each pair of keels are braced by its false bottom F', being corrugated and having ducts P' communicating 125 with chambers C'. The upper surface of the board E' may be concave in cross-section, as shown in Fig. 10, wherein the body of the person swimming on the raft is intended to lie, and the lower surface of the said board may 130 be corrugated or not, as desired. Braces a' are intended to be employed to strengthen the several parts of the boat.

Having thus fully described my invention,

what I claim, and desire to secure by Letters Patent, is—

1. A vessel provided with a plurality of keels, air-chambers situated between the said keels and having contracted downwardly-opening mouths, substantially as described.

2. A vessel provided with a plurality of keels, air-chambers situated between said keels and having contracted downwardly-opening mouths, the bottoms of the said air-chambers being provided with transverse corrugations, substantially as shown and described.

3. A vessel provided with a plurality of keels, air-chambers between the keels, and air-cavities having contracted downwardly-opening mouths situated between the keels, the channels constituting means for communication between the external air and the air-cavities, substantially as described.

4. A vessel having self-filling air-chambers and corrugations arranged along its bottom, a plurality of keels, and air-channels formed by said keels and constituting a means for communication between the chambers and corrugations and the external air at the vessel's bow, substantially as described.

5. A vessel having a plurality of keels, T-shaped pieces situated between the keels, channels formed by said keels and the T-shaped pieces, air-chambers situated between the vessel's bottom, the keels and the T-

shaped pieces, and having communication with the channels, said channels being adapted to conduct air thereto from above the water-line at the vessel's bow, substantially as described.

6. A vessel having a plurality of keels forming air-channels, detachable T-shaped pieces situated between the keels and forming therewith and with the vessel's bottom cavities having contracted mouths communicating with the channels, substantially as shown and described.

7. A vessel having with its bottom E, a false bottom F with perforations, a plurality of keels supporting the false bottom and forming therewith an air channel or channels having external communication above the water-line at the vessel's bow, partitions situated between the bottom E and the false bottom F and forming with the same and the keels air-chambers, said channels and the perforations constituting means for conducting air to the chambers from above the water-line at the bow of the vessel, substantially as described.

In testimony whereof I affix my signature in presence of two witnesses.
